METALLIC SHADE ROLLER

Filed Oct. 29, 1929

UNITED STATES PATENT OFFICE

WILLIAM OSKAR NICOLAUS SÖDERQVIST, OF LIDKOPING, SWEDEN

METALLIC SHADE ROLLER

Application filed October 29, 1929, Serial No. 403,231, and in Sweden October 3, 1929.

This invention relates to shade rollers and more especially to such rollers made of metal. One object of this invention is to provide shade rollers of metal which are easy to manufacture.

Another object of my invention are metallic shade rollers which are rather light so that they do not need but rather simple suspension means.

10 A further object of this invention is a metallic shade roller that can be manufactured in standard lengths and easily extended or restricted in its standard length when procured to suit a certain window casing or 15 other place for utilization.

Still a further object of the invention is the provision of ready means for attaching the shade to the metallic roller so that such an operation can be carried out by anybody 20 without preparatory experience.

In the accompanying drawing two embodiments of my invention are illustrated whereby

Fig. 1 shows the new shade roller in its simplest embodiment applied to a window casing,

Fig. 2 shows the same parts but the roller of an extensible embodiment,

Fig. 3 shows on an enlarged scale the one 30 end portion of an extensible roller illustrating in detail the mechanism for its extension,

Fig. 4 is a cross section on the broken line A—B—C—D in Fig. 3 looking in the direction of the arrows,

Fig. 5 is a cross section on the line E—F in Fig. 3 looking in the direction of the arrows,

Fig. 6 is a plan view of a stiffening bracket before its mounting,

Fig. 7 is a cross section on line G—H in 40 Fig. 6,

Fig. 8 is a cross section of a portion of the roller showing the attachment of the shade to the roller,

Fig. 9 is a plan view of a clamping member 45 for said attachment.

Figures 8 and 9 are on a still more enlarged scale than the other figures. All figures except Figs. 6 and 9 show the parts wholly or partially in section.

In the drawing similar parts are designated with the same figures or reference.

The shade roller 1 is built up like a skeleton of longitudinal strips or bands 2 of iron or steel or some other suitable metal, stiffened by suitably spaced brackets 3 of sheet metal.

50 The body of the brackets 3 has a substantially circular form with a central boring 4 to reduce the weight and to allow the throughgoing of a rod or other members which can be wanted for some needs which do not belong to this invention and therefore are not shown nor described here in order not to complicate the drawing and description. Said members for instance can be such spiral springs which are generally known as motors for automatically operated window shades.

55 The bands 2, which preferably are hardened and annealed to a springing ability in order to afford a better firmness of the roller, are spaced round the circular brackets 3 as clearly shown in Figs. 4 and 5 so that the outer appearance of the complete roller equals a cylindrical member such as are the usual window shade rollers of wood or metal tubes.

60 The two ends of the roller are closed by covers or brackets 5 of substantially the same appearance as the brackets 3 but without boring 4 and instead provided each with a projecting pin 6 as journals for the rotary suspension

65 of the roller in brackets 7 on the window casing 8 or generally speaking on the place where the shade is to be utilized. These pins 6 can be substituted by a rod which passes through the entire roller through the borings 4 in the brackets 3 and constitutes the journals at both ends of the roller which rod may be fixed to the end brackets 5 in any convenient way so that the rod will revolve integral with the roller.

70 As such a rod and its attachment to the 75

75

80

85

roller can be effected in a plurality of manners which all are easily understood by anybody, and as these means do not make part of the invention they are not shown in the drawing. Likewise I have not illustrated any means for operating the roller as such means can be of different classes, all of some known design. For instance the roller can be provided at one end with a sheave and a core for the old fashioned method of operating a rolling shade by pulling the core, or it can be provided with a spiral spring motor for the automatic revolving of the roller. In the last mentioned case the bracket 5 at the spring provided end of the roller must be substituted by some revolving member. Such devices, however, are well known in automatically operated shades and do not belong to this invention and they do not want to be illustrated here.

The attachment between the strips 2 and the brackets 3 and 5 is carried out in the following way. Each bracket 3 is provided with so many tongues or lugs 9 as is the number of longitudinal strips 2 which lugs project radially as shown in Figs. 6 and 7 when the bracket 3 not yet has been mounted in the roller skeleton. In the shown example there are three such strips 2, and consequently the lugs 9 are three in number on each bracket. Each strip 2 on the spot where a bracket 3 is to be applied is provided with a substantially rectangular hole 10 of the same length as the width of a lug 9, and the same width as the thickness of said lug. Said holes 10 are produced in the strips 2 by pressing down a portion 11 of the strip, by which down pressing the hole 10 appears in the one wall of said recess. Between each two lugs 9 each bracket 3 has a flange 12 directed at right angle to the surface of the bracket as shown in Fig. 7.

When assembling the skeleton the lugs 9 of the brackets 3 are inserted each through a hole 10 in the strips 2 and bent down in the length direction of the strips 2 whereby the lugs fill up their respective recesses 11 so that the outer surface of the strips 2 comes in flush with the outer surface of the down bent lugs 9 as can be clearly seen in Fig. 3. Hereby the flanges 12 register with the interspaces between two adjacent strips 2 as shown in Figs. 4 and 5, and as a result the whole circumference of the assembled roller will be a substantially continuous circular line. The brackets 5 are provided with a collar 13 projecting at right angle from the surface of the bracket, so that when assembled the outer surface of collar 13 lies in flush with the outer surface of the strips 2 which are bent down at their ends as shown by 14 in Figs. 1, 2 and 3, and passed through substantially rectangular holes in the brackets 5 close inside the collar 13. On the outer

surface of brackets 5 the throughgoing ends 15 of the strips 2 are bent down as shown in Fig. 3.

Figs. 2 and 3 show how the roller can be adjusted as to the length by means of an end piece 17 built up substantially of similar scantlings as the body portion of the roller, viz. of strips 2^a and an end bracket 5 whereby the body portion of the roller at this end can be left without such an end bracket as shown in Fig. 3. The extensible strips 2^a are provided on both sides with lugs 18 which are bent down so as to embrace the adjacent strips 2 as shown in Fig. 5, and thereby assembling the extensible portion 17 with the body portion. The strips 2 of the body portion are recessed within the range of the extensible portion 17 as shown by 19 in Figs. 2 and 3 so that the extensible strips 2^a come in flush with the body strips 2 as it concerns their outer surface. When the extensible portion 17 has been slid along the body portion, guided by the clamping lugs 18, until the total length of the roller suits the window casing 8 where the shade is to be suspended, the lugs 18 are compressed around the body strips 2, and thus the roller made rigid as an integral piece of a certain length.

If a roller specimen is to be removed from its present place, and to be used at another place with some other width, the roller can be further extended or reduced as the case may be by slight hammering knocks on the respective ends of the extensible strips 2^a whereby these will slide along the body strips 2 until the wanted new total length is reached.

The shade 20 can be readily applied to the roller 1 by means of clamps 21, shown in Figs. 8 and 9 which clamps comprise narrow metal strips with double bent ends 22 with sharpened points. These clamps are laid above the upper portion of the shade 20 which has been applied to one of the strips 2 (and the corresponding extensible strips 2^a in the case of the extensible embodiment) whereupon the ends 22 are bent over as shown in Fig. 8, whereby the sharp point at the down end of the clamp 21 penetrates the shade. By compressing the double bent ends 22 the clamps are fixed to the strips 2 (2^a) and thus the shade stationarily attached.

Having thus described my invention what I claim is:

1. A shade roller comprising a plurality of circularly alined strips, said strips having formed therein apertures and adjacent recesses, said recesses being below the plane of the strips, circular brackets confined by the strips and having peripheral projecting lugs passable through said apertures and bendable into said recesses, brackets upon the ends of the roller, and means carried by the latter brackets for rotatably supporting the roller.

2. A shade roller consisting of a plurality
of circularly alined metal strips, circular
brackets confined by the strips, said strips
having apertures therein, recesses adjacent
5 said apertures, said brackets having pe-
ripheral lugs passable through the apertures
and bendable into the recesses, axially extend-
ing flanges carried by the brackets, said
flanges having their side edges intimately en-
10 gaged with the sides of the strips between
which they engage, said flanges being of
a length less than the strips, brackets upon
the ends of the roller, and means carried there-
by for rotating the supporting roller.

15 In testimony whereof I have affixed my sig-
nature.

WILLIAM OSKAR NICOLAUS SÖDERQVIST.
